UNITED STATES PATENT OFFICE.

JAMES C. BOWEN, OF NORTH SPRINGFIELD, VERMONT.

REFRIGERATOR.

SPECIFICATION forming part of Letters Patent No. 236,765, dated January 18, 1881.

Application filed August 18, 1880. (No model.)

To all whom it may concern:

Be it known that I, JAMES COLMAN BOWEN, of North Springfield, in the county of Windsor and State of Vermont, have invented a new and useful Improvement in Refrigerators, of which the following is a specification.

Refrigerators have been used to supply air to cars made air-tight and surrounded with non-conducting material; but I have found that this is not sufficient; that it is necessary to provide for forcing the air several times around through the articles in the car, and with the air already in the car back and through the ice-box, so as to bring all the air and articles in the car to a uniformly cold temperature. This I accomplish by allowing the cold air from the bottom of ice-box to fall directly to the bottom of car and force the warm air through the top of car, and in at the top of ice-box, whence it passes over the ice. After passing several times around through car and ice-box all the air becomes alike cold, and the temperature in the car will not be so readily lowered afterward below the point desired.

In the accompanying drawings, Figure 1 is a longitudinal vertical section, representing a railway-car in connection or communication with a refrigerating apparatus for the purpose of cooling its interior and contents. Fig. 2 is a longitudinal horizontal section of the car.

Similar letters of reference indicate corresponding parts.

A represents a railway-car, which may be of any construction which will render it suitable for the transportation of provisions or fruits. Near one end of the car is a vertical partition, B, extending transversely from side to side and from the top of the car nearly to the bottom, so as to form a vertical flue, C, with an opening, d, at the bottom thereof, leading to the interior of the car. The top of this flue C is provided with a gate or cut-off, E, for the purpose of closing it when desired. In the top of the car, at any suitable point, is an opening, f, provided with a gate or cut-off, G, which may be closed when desired.

H represents a stationary refrigerating apparatus, consisting of a chamber or receptacle for ice. Near one end of the chamber H, in the bottom thereof, is an opening, in which is a vertical pipe, J, the upper end of which extends somewhat above the bottom of the

chamber, and the lower end extends considerably below the exterior of said bottom, in order to communicate with the flue C, as hereinafter described. At the end of the chamber H farthest from the pipe J, and near the top of said chamber, is an opening, i, which communicates with a vertical pipe, K, the lower end of which extends considerably below the bottom of the chamber, for communication with the opening f in the top of the car.

The pipe J is provided with a valve, L, which may be closed so as to cut off communication with the exterior of said pipe, and the opening i is provided with a gate, M, for a similar purpose. The lower ends of the pipes J and K are provided with telescopic sliding tubes P P², to accommodate them to cars or other receptacles of different heights.

The car or receptacle A, having received the contents which are to be transported therein, is run under the refrigerator H, and the pipes J and K are connected with the flue C and the opening f. The valves or cut-offs L, E, G, and M are then opened, so as to allow communication between the chamber H and car A. The cold air passes down the pipe J and flue C into the car A, and the warmer air escapes from the car through the opening f and passes up through the pipe K and into the ice-chamber H, as indicated by the arrows in Fig. 1. When the air in the car has been sufficiently cooled the valves or cut-offs are closed and the car is disconnected from the ice-chamber and placed in position for transportation.

I am aware that it is not broadly new to furnish air-tight cars with cold air from a stationary refrigerator before they are started for their destination with meats, fruits, or other products; but

What I claim is—

A stationary refrigerator for supplying cars with cold air, consisting of the ice-box H, having the valved opening i near the top, the pipe K to connect it with the top of car, and the valved pipe J to connect with a pipe or flue leading to the bottom of car, whereby, when above the car, the air can be circulated several times through the car, as described.

JAMES COLMAN BOWEN.
